UNITED STATES PATENT OFFICE.

HANS T. WALROW, OF NEW YORK, N. Y.

FOLDING CROSS.

1,032,257.

Specification of Letters Patent.

Patented July 9, 1912.

Application filed June 22, 1911. Serial No. 634,684.

To all whom it may concern:

Be it known that I, HANS T. WALROW, a citizen of the United States, and a resident of the city of New York, Astoria, borough 5 of Queens, in the county of Queens and State of New York, have invented a new and Improved Folding Cross, of which the following is a full, clear, and exact description.

10 My invention relates generally to articles of jewelry intended for ornamental purposes on watch chains, and more particularly involves a folding cross.

15 The object of my invention is to provide a folding cross of new and improved construction, which will be pleasing in its appearance and well adapted to serve as an article of adornment.

20 A further object of the invention is to provide a device of the class described, which will afford a pleasing ornament in connection with the watch chain, the construction thereof setting forth a cross, one of the members being pivotally mounted 25 and adapted to be folded within the other member.

Reference is to be had to the accompanying drawings forming a part of this specification, in which similar characters of reference indicate corresponding parts in all 30 the views, and in which—

Figure 1 is a perspective view of the cross in open position; Fig. 2 is a side view thereof, in folded position; Fig. 3 is a transverse 35 sectional view on the line 3—3 of Fig. 2; Fig. 4 is a vertical sectional view of a modification, showing means for holding the parts fixed; Fig. 5 is a modification of the form shown in Fig. 1, and Fig. 6 is a further 40 modification.

Referring particularly to Figs. 1, 2 and 3, the device is made up of one member 1 and another member 2, the member 1 being provided with a slot 3 extending therethrough 45 and the member 2 being pivotally supported at 4 within the slot, between the side walls thereof.

The width of the member 1 is substantially the same as the width of the member 50 2, and the width of the slot 3 is substantially equivalent to the thickness of the member 2, so that the member 2 is adapted to be folded within the slot 3, as shown particularly in Fig. 2. A step 5 of any suitable form of 55 construction is extended transversely of the member 1, on one side thereof, the purpose

being to limit the travel of the member 2, whether in unfolded or folded position.

In order to afford simple means for unfolding the parts, I have provided one corner of the member 2 with a lug or projection 6, whereby it may be engaged by a person's finger, this lug, in folded position, engaging within a suitable recess 7 adjacent the top of the member 1. In order to provide means for suspending the article from a chain or a brooch or a pin, the top of the member 1 is provided with an eye 8, through which a suitable chain or ring may be engaged. In some cases it may be desirable to secure the members 1 and 2 in any relative position whether folded or unfolded, and in order to insure this I have provided in the device shown in Fig. 4 a thumb screw 9, engaging in threaded openings in the member 1, whereby tightening of this thumb-screw will bring these sides closely together, with the member 2 secured in any desirable position.

Fig. 5 shows a further modification, in 80 that the member 1^a is provided with a recess 3^a into which the member 2 is adapted to be positioned, the two parts being pivotally mounted, as at 4. The thickness of the lower portion of the member 1^a is substantially equal to the recessed portion of this member, plus the thickness of the transversely extending member 2, so that when the parts are folded, as shown in Fig. 5, 85 there will be no projecting corners.

It is not essential that the member 1^a be recessed to accommodate the member 2, since the form shown in Fig. 6 is equally well adapted for my purpose, this consisting simply of two pivoted members 1^b and 2^b, 90 with a suitable pivot 4^b passing therethrough.

If desired, suitable engraving may be provided on each of the members 1 and 2, in order to express some thought or sentiment, and, as shown in Fig. 1, I provide the words 100 "God's will" on the member 1, and "My will" on the member 2, the thought to be conveyed being that "My will should depend on and be included within God's will."

From the above description it will be seen 105 that I have devised an article of jewelry of an improved construction, and which is not only well adapted to serve the purpose of such an article, but is equally well adapted to show and express a beautiful sentiment 110 on the part of the wearer. Of course, it is obvious that in showing this device I have

not limited myself to the exact proportions used, nor to the words which I have shown engraved thereon, these features being capable of change, such changes being included 5 within the scope of the appended claims.

Having thus described my invention, I claim as new and desire to secure by Letters Patent:

1. As an article of jewelry, a cross made 10 up of two members in pivotal relation with each other at points intermediate of the ends of each, one of the members being provided with a slot through which the other member extends, a stop on one side of the 15 first member, a recess on the side of the first member, a lug adjacent one end of the second member adapted to be received within the said recess when the second member is contained within the said slot, the side 20 thereof being in engagement with the said stop, the lug providing means whereby the second member may be moved out of the slot about the pivotal supporting means.

2. As an article of jewelry, a cross made 25 up of two members in pivotal relation with each other at points intermediate of the ends of each, one of the members being provided with a longitudinally extending slot within which the other member is mounted, a 30 recess in one side of the first member, a lug carried by the second member adapted to be received within the recess when the second member is included within the slot in the first member, the lug affording means 35 for moving the second member out of the slot about its pivotal support, the pivotal supporting means embodying a thumb screw whereby the relative positioning of the second member on the first may be maintained.

3. As a new article of jewelry, a cross comprising two members in pivotal relation with each other at a point intermediate the

ends of each and midway the ends of one of the members, the first member being provided 45 with a slot into which the second member is adapted to be positioned, the dimensions of the said slot being substantially equal to the dimensions of the said second member, whereby the said second member 50 may substantially fill the said slot.

4. As a new article of jewelry, a cross comprising two members in pivotal relation with each other at a point intermediate the ends of each, the first member being provided 55 with an eye, whereby the article may be suspended, the said member being also provided with a slot into which the second member is adapted to be positioned, the dimensions of the said slot being such that the 60 second member, when moved about the pivotal support, may be positioned within the said slot.

5. As an article of jewelry, a cross made up of two members in pivotal relation with 65 each other at points intermediate the ends of each, one of the members being provided with a slot through which the other member extends, means carried by the first member for engagement with the second member 70 when the second member extends transversely of the first, whereby such transverse position is determined, and means carried by the second member for engagement with the first member when the second member 75 extends longitudinally of the first member, whereby such position of the parts is determined.

In testimony whereof I have signed my name to this specification in the presence of 80 two subscribing witnesses.

HANS T. WALROW.
